YARN PRINTING MACHINE

Henry F. Shaffner, Winston-Salem, N. C., assignor to Briggs-Shaffner Company, Winston-Salem, N. C., a corporation of North Carolina

Application December 12, 1930
Serial No. 501,933

3 Claims. (Cl. 101—172)

This invention relates to new and useful improvements in yarn printing machines.

Among the several objects of the invention are to provide a machine for printing or dyeing warp yarn with a plurality of colors; to provide means for successively printing the yarn with different colors while the yarn is being fed through the machine; to provide the machine with a plurality of printing couples including printing rolls having interchangeable printing plates whereby variations in the lengths of the printed portions of the yarn may be obtained; to provide means for supporting the printing rolls in operative relation to the dye rolls and to include constructions whereby said printing rolls may be readily moved away from their operative positions for the purpose of loading the machine or for obtaining access to the dye rolls; to provide the printing couples with dye transfer rolls and means for supporting the same whereby they may be either moved into operative engagement with the dye rolls and retained in said engagement or moved away from the dye rolls for the purpose of inspecting the latter; to provide gear driving connections between all of the rolls of all the couples for positively rotating said rolls; to provide a front feeding couple for the yarn and to drive the same by gearing in timed relation with the printing couples; to provide separate dye pans for the respective dye transfer rolls; to provide a steam box common to all of the dye pans for maintaining the dye in proper liquid condition, and to provide a vertically adjustable table for supporting the steam box and dye pans whereby the latter may be moved into and out of cooperative relation with the dye transfer rolls.

With these and other objects in view which will more fully appear, the nature of the invention will be more clearly understood by following the description, the appended claims, and the several views illustrated in the accompanying drawings.

In the drawings:—

Figure 1 is a front elevation of a printing machine constructed in accordance with my invention.

Figure 2 is a top plan view thereof.

Figure 3 is a vertical longitudinal sectional view thereof.

Figure 4 is a transverse sectional view taken on the line 4—4 of Figure 3.

Figure 5 is a fragmentary elevation of the rear side of the machine.

Figure 6 is a detail perspective view of the roll adjusting means.

Figure 7 is a sectional view through the roll adjusting means.

Figure 8 is a perspective view of the printing roll, and

Figure 9 is a cross sectional view of the printing roll.

Referring to the accompanying drawings, my invention comprises a main frame A having front and rear skeleton plates or walls 5, 5 which are rigidly connected together by suitable transverse braces, each wall being provided with an opening 6. Supported on the main frame at the left hand end thereof is a feeding couple B, and supported on the main frame at the right hand end thereof is a guide reel C. Supported on said main frame and disposed between the feeding couple B and the guide reel C is a plurality of printing couples D, D, D, D. The feeding couple B includes an upper feed roll 7 and a lower feed roll 8, and each printing couple D includes an upper or printing roll 9 and a lower or dye roll 10. The feeding couple B and the printing couples D are disposed in a horizontal plane, with the printing rolls 9 all being disposed above a horizontal line coincident with the meeting line of the feed rolls 7 and 8 and the dye rolls being all disposed below said line. The lower feed roll 8 and the lower or dye rolls 10 are respectively fixed to spaced transverse shafts 11 which are journaled at their ends in bearings 12 secured to the upper edges of the side walls or plates 5, 5 of the main frame A, and fixed to the front end of each shaft is a drive gear 13. Intermediate the drive gears 13 and in constant mesh therewith are idle gears 14 which are journaled on a plate 15 secured to the front plate 80 or wall 5 of the main frame by bolts 16, 16. These gears 13 and 14 are rotated from a drive shaft 17 journaled on the right hand end of the main frame by means of a drive gear 18 fixed to the shaft and meshing with the adjacent dye roll 85 gear 13.

The upper feed roll 7 and the upper or printing rolls 9 are independently mounted on the main frame A by similar means whereby said rolls may be separately moved toward and from the cooperating rolls whenever it is desirable to load the machine or to inspect any or all of the lower rolls and whereby the upper rolls will be retained in cooperative relation with the lower rolls. Each of these supporting means includes a frame 19 consisting of spaced parallel front and rear arms 19^a, 19^a which are fixedly connected to a horizontal pivot rod 20 which extends transversely of the main frame and is journaled in posts 21, 21 attached to the upper portions of the side plates 110.

or walls 5, 5 of the main frame. The roll is fixed to a shaft 22 which is journaled in the arms 19^a, 19^a, and the pivot rod 20 or axis of the supporting frame is disposed at one side of the roll 5 and parallels the shaft 22 of the roll. The free ends of the arms 19^a, 19^a are respectively provided with forwardly and rearwardly extending forked arms 23, 23 which are located on the opposite side of the roll from the pivot rod 20. Associated with 10 each roll supporting frame are arms 24, 24 which are normally disposed vertically, and are fulcrumed at their lower ends to pivot pins 25, 25 mounted on the lower portions of the posts 21. These pivot pins 25 are located on that side of 15 the roll opposite the fulcrum 20 of the roll supporting frame and their axes are parallel with said fulcrum in order to permit the arms to be swung forwardly and rearwardly in a vertical plane parallel with the axis of said supporting 20 frame. The upper end of each arm 24 is threaded and projects upwardly between the forked arms 23, 23 of the adjacent arm 19^a of the roll supporting frame. A collar 26 is disposed around the arm 24 for slidably movements therealong below 25 the forked arms 23, 23, and a coil spring 27 is disposed around the arm 24 below the collar to yieldingly support the latter and consequently the roll against downward movement. A sleeve 28 is threaded on the arm 24 above the forked arms 23, 30 23 and a lock nut 29 is threaded on the arm 24 above the sleeve 28. The inner faces of the forked arms 23, 23, the collar 26, and the sleeve 28 are formed with convex engaging surfaces whereby the roll supporting frame may be readily swung 35 above its axis without any binding action, upon adjustments of the lock nut 29 and the sleeve 28.

Fixed to the front ends of the shafts 22 of the upper rolls are gears 30 which mesh with the drive gears 13 of the lower rolls when the upper rolls 40 are in operative positions. When any one of the upper rolls is swung upwardly, the gear couple 22, 13 is broken as will be understood.

Each of the dye rolls 10 is provided with a peripheral layer 31 of felt or other soft material 45 which is saturated with dye.

The printing rolls 9 are normally spaced above the dye rolls 10, and each printing roll is provided adjacent each end with a circumferential series of equally spaced tapped openings 32. One 50 or more segmental plates 33 are positioned against the periphery of the roll, and each plate is provided adjacent each end with a series of equally spaced openings 34 which register with certain of the openings 32. Screws 35 are employed in said registering openings for fastening the plate or plates to the roll. It will be understood that there may be one or more printing plates 33 on each roll, and that the widths of these plates may vary. Thus when the printing 55 rolls are in operative positions the printing plates will successively and intermittently depress the yarn into contact with the dye saturated layers 31 of the dye rolls and thereby print or dye the yarn with different combinations of colors and 60 with either like or different lengths.

Disposed below the dye rolls 10 and normally arranged in surface contact with the layers 31 of said rolls, are dye transfer rolls 36. Each of these transfer rolls 36 is journaled on a supporting frame 37 which is similar to the supporting 70 frame 19, and a vertically disposed arm 38, similar to the arms 24, is associated with each frame 37 so as to permit the transfer roll to be moved upwardly or downwardly and into or out of contact with the associated dye roll 10.

Supported on the main frame A for vertical adjustments between the side plates or walls 5, 5 thereof, is a horizontal table 39. Supported on this table is an elongated open topped steam box 40 and mounted in said box is a plurality of 80 separate dye pans 41 arranged in a series directly under the respective transfer rolls 36. The table may be raised by manual means and retained in its adjusted position so as to dispose the dye pans in cooperative relation with the 85 transfer rolls whereby the latter will pick up dyes and transfer the same onto the dye rolls 10. Steam is admitted to the steam box 40 through the medium of a flexible pipe 42 which permits the steam box to be raised and lowered while maintaining operative connection with said steam pipe. Each transfer roll 36 is provided with a gear 43 which is in constant mesh with a gear 44 fixed to the dye roll 10. Thus when any one or all of the transfer rolls 36 are lowered the gear driving connections between the dye rolls 10 and the transfer rolls 36 become broken. Whenever, it is desired to inspect or repair the 90 dye rolls 10, the transfer rolls may be lowered so as to give the operator access to the dye rolls. Before the dye rolls are lowered, however, it is necessary to lower the table so as to lower the 95 dye pans a distance sufficient to permit the transfer rolls to be lowered the necessary distance.

In order to raise or lower the table, I have provided the main frame A with two pairs of vertically disposed racks 45. Journaled in suitable bearings fixed to the under side of the table and at each end of the table is a transverse shaft 46 having pinions 47, 47 fixed thereon. These 100 pinions are in constant mesh with the associated pair of vertical racks 45. Also fixed on each shaft 46 is a worm gear 48. An operating shaft 49 extends longitudinally of the table and is journaled in suitable bearings mounted on the under 110 side thereof. Fixed to the operating shaft 49 is a pair of worms 50, 50 which respectively engage the worm gears 48, 48. Thus upon rotation of the operating shaft 49 motion will be transmitted to the pinions 47, 47 and by reason of 115 these pinions being in constant mesh with the vertical racks, the table will be raised or lowered as will be readily understood.

From the foregoing, it will be apparent that I have provided a yarn printing machine whereby 125 the yarn may be printed or dyed with a plurality of colors; that the lengths of the coloring on the yarn may be readily varied; that the printing rolls are mounted for independent adjustment relative to the associated dye rolls; that the printing rolls as well as the transfer rolls are independently movable toward and from the dye rolls so as to permit the machine to be readily loaded 130 with yarn and also to permit ready inspection of the dye rolls, and that the steam box is common to all of the dye pans whereby the dye in the several pans is maintained at uniform temperatures.

I claim:

1. In a yarn printing machine, the combination with a plurality of printing couples, each including an upper printing roll and a lower dye roll, separate dye pans respectively located in cooperative relation with the dye rolls, and a steam box common to all of said pans.
2. In a yarn printing machine, the combination with a plurality of printing couples, each including an upper printing roll and a lower dye roll, a vertically movable table disposed below said couples, separate dye pans mounted on said

table for cooperation with the respective dye rolls, a steam box mounted on the table and common to all of said pans, and means for raising and lowering said table together with the steam box and 5 dye pans.

3. In a yarn printing machine, the combination with a plurality of printing couples each including a printing roll and a dye roll, the dye roll being provided with a peripheral layer of soft 10 absorbent felt-like material, of a segmental printing plate mounted on the printing roll and having a smooth outer surface adapted to periodical-

ly contact the absorbent peripheral layer of the dye roll and press the yarn into said layer, the outer surface of the plate being concentric to the axis of the printing roll and extending for not less than 60 degrees around the periphery of the roll, the plates being disposed on their respective rolls at different radial relations, means for supplying printing fluid to the absorbent periphery of said dye roll, and means for rotating said printing rolls in unison. 80 85
